PUMPING DEVICE AND METHOD

Howard W. Parker, Park Ridge, Ill., assignor to
 The E. H. Wachs Company, Chicago, Ill., a corporation of Illinois

Application May 21, 1931, Serial No. 538,964

8 Claims. (Cl. 230—108)

The invention relates to pumping devices and to methods of pumping. The present invention relates generally to devices of the type disclosed in my copending application Serial No. 5 495,876 filed November 15, 1930, of which the present invention is a continuation in part.

In general, the aim of the invention is to provide a pumping device which is simple and sturdy in construction, which embodies very few 10 parts subject to operating wear or damage, is highly efficient in operation, and is capable of adaptation for manifold uses.

An object of the invention is to provide a novel pumping device in which a decreased pressure created by cavitation is utilized to produce 15 the pumping action.

Another object is to provide a pump embodying a member mounted for rotation and having means thereon for creating decreased pressure by cavitation, and means for utilizing the decreased pressure to produce a flow from a 20 source of fluid to be pumped.

A further object of the invention is to provide a novel device for creating a source of decreased pressure which includes means for 25 producing jets or streams of fluid moving flatwise at or above a critical speed whereby regions of decreased pressure are formed by cavitation.

30 More specifically stated, an object of the invention resides in the provision of a pumping device in which a member, rotatably disposed in a fluid has means thereon for creating a plurality of jets or streams of such fluid arranged 35 to discharge substantially radially of the member and to travel laterally in the general direction of rotation of the member at the point of discharge, whereby each jet produces a following region of decreased pressure by cavitation; said 40 member having means associated therewith for preserving the character of the streams until the effectiveness thereof is substantially dissipated, and means for establishing communication 45 between said regions of decreased pressure and a source of fluid to be pumped.

Another object of the invention is to provide a novel method of pumping which embodies the production of a pumping pressure by cavitation.

50 A further object is to provide a novel method of pumping which includes the steps of forming moving jets or streams of fluid within a main body of fluid to create regions of decreased pressure behind said streams, preserving the character 55 of the streams until the working force

thereof is dissipated, and establishing communication between the said regions and a source of fluid to be pumped.

Other objects and advantages will become apparent in the following description and from 60 the accompanying drawing, in which:

Figure 1 is a longitudinal axial section through a device embodying the features of the invention.

Fig. 2 is a transverse section through the 65 device taken substantially along the line 2—2 of Fig. 1.

Fig. 3 is a fragmentary and enlarged detail view showing the peripheral face of the rotating member.

Broadly, the present invention utilizes the principle of cavitation to produce a decrease of pressure within a body of fluid, which pressure decrease is employed as the pumping force. In the sense in which the term is herein employed, 70 "cavitation" may be defined as that formation of a region of decreased pressure which is produced when an object moves at such a velocity or speed through a fluid that the pressure within the region, immediately behind the object, is 75 reduced below that amount of pressure which would preserve the natural flow of fluid to said region. In creating and using this force for pumping purposes, the present invention embodies a member journaled for rotation with a 80 body of fluid, which member has a plurality of nozzles thereon arranged to produce, when the member rotates, powerful jets or streams of fluid which are discharged substantially radially of the member and which move laterally through 85 the body of fluid. The velocity of lateral movement of these jets is above the critical speed at which cavitation results so that each stream is, in effect, the object which moves through the body of fluid for producing a region of decreased 90 pressure. Means are provided for establishing communication between such regions and a source of fluid to be pumped.

The present structure further provides a plurality of members associated with the rotating member for interrupting the discharged jets, which members are arranged to preserve the character of the stream until the working force thereof is substantially expended and, in general, to increase the cavitating efficiency of the jets.

The substance in which the rotating member is immersed, as well as the pumped substance, are herein characterized generally as fluids, but the most efficient operation of the pump occurs when there is a considerable difference in the 110

comparative densities of the fluids. As a specific example of one use, the pump may be employed to evacuate a container, in which case a satisfactory immersing fluid is water, while the fluid 5 to be pumped is air or another gas.

Referring more particularly to the drawing which illustrates merely for descriptive purposes, a particular form of device embodying the features of the invention, 10 designates generally a 10 casing section having bearings 11 therein arranged rotatably to support a shaft 12. One end of the shaft 12 extends from the casing and carries a suitable member 13 by which the shaft may be connected with any well-known type of 15 prime mover (not shown). The casing section 10 has a flat end wall 14 preferably formed integrally therewith, through which wall the end of the shaft 12 extends a short distance, a conventional type of packing gland 15 being inter- 20 posed between the shaft and the end wall. The casing section 10 has, adjacent the end wall 14, a radial flange 16 extending a short distance axially beyond the end wall to provide an annular shoulder 17 which defines a circularly- 25 shaped recess 18 facing outwardly from the end wall.

A second casing section 19 has a flange portion 20 thereon, fashioned substantially as the complement of the flange 16, and a centrally offset portion 21 which is disposed in opposition to the recess 18 when the sections are assembled. The recess 18 and the offset portion 21 thus provide a closed compartment 22 within the casing. The flanges 16 and 20 are provided with annular 30 depressions 23 which, when the parts are assembled, define an annular bore 24. The bore 24 communicates with the compartment 22 through a radially extending and outwardly flaring passageway 25 provided between the face 35 of the shoulder portion 17 of the flange 16 and the complementarily shaped, opposing face of a portion 26 of the flange 20.

The end of the shaft 12, within the compartment 22, carries a member for rotation therewith, which member is herein shown as comprising a disk 27 of such dimensions that it fits 40 relatively snugly within the recess 18. The disk 27 carries means by which jets or streams of fluid are discharged outwardly of the disk in the rotation thereof. One form of such means is shown 45 in Fig. 2 as comprising a plurality of lateral projections or lugs 28 formed on or secured to the side face of the disk opposite the wall 14 and arranged in spaced annular series adjacent the 50 periphery of the disk. The rear or trailing face 29 of each projection (with reference to the direction of rotation of the disk), and the front or advancing face 30 are cut away to provide opposing faces on adjoining projections which define nozzles 31. Preferably the nozzles taper 55 from the center of the disk and are directed substantially radially thereof.

Adjacent the nozzle forming surfaces, the 60 projections are fashioned to provide enlarged pockets 32 opening toward the axis of the disk to entrap and deliver fluid to the nozzles. In forming the pockets, the front face of the projections are preferably recessed arcuately, as at 65 33, while the opposing rear faces slope sharply 70 forwardly, as at 34, from the rear nozzle defining surfaces 29. The surfaces 33 and 34 on the same lug meet to form a sharp knife-edge 35 facing forwardly in the direction of rotation of the disk.

75. The disposition of the projections 28 with

reference to the casing sections 10 and 19, is such that the peripheral faces of the lugs are disposed substantially adjacent to the inner or restricted mouth of the flaring passageway 25 whereby, as the disk rotates, jets of fluid discharged from each nozzle 31 flow through the passageway 25 into the bore 24.

While any suitable means may be utilized to insure rotation of the disk with at least the peripheral portion thereof immersed in the fluid, it has been found desirable constantly to cause a circulating flow of said fluid through the device. For this purpose, the casing section 19 has an inlet passageway 36 (Fig. 2) communicating through the wall of the offset portion 21 with the closed compartment 22. An inlet port 37 to the passageway 36 is defined by a flange 38 to which a conduit (not shown), leading to a source of fresh fluid, may be secured. An outlet passageway 39 preferably located substantially oppositely of the passageway 36 communicates with the bore 24 and has a flange 40 defining an outlet port 41. The flange 40 provides a connection with a conduit (not shown) for conveying discharged fluid from the device. Generally, discharge is to a suitable separating device (not shown) wherein a natural separation of fluids may take place at atmospheric pressure.

The operation of the parts, as they have thus far been described, is as follows: A constant stream of fluid is delivered to the compartment 22 through the passageway 36 where it comes into contact with the exposed face of the rapidly rotating disk member 27. It is well recognized that, when a member rotates in a body of fluid, skin friction between the face of the member and fluid produces a flow of the fluid in the direction of rotation of the member at a velocity which is approximately equal to one-half the velocity of rotation of the member. Also, centrifugal action causes any particle of water to travel outwardly from the axis of rotation. The resultant of these forces causes the water flow to approach the periphery of the disk at an acute angle.

The preferred formation of the projection faces 33 and 34, which define the pockets 32, is such that the inlet mouths of the pockets face oppositely of the direction of flow of the water thereto. Moreover, the angular slope of the rear face 34 of each projection is determined by and corresponds with the angle at which the water flow approaches the periphery of the member. Theoretically, these angles should be exactly the same so that any fluid not entrapped in one pocket may flow smoothly along the rear face of the next projection into a succeeding pocket. This formation avoids and eliminates the creation of regions of decreased pressure behind the projections by cavitation.

It will be evident that the fluid thus entrapped within the pockets will rotate at the same velocity as the pockets themselves, and will then have a certain additional centrifugal force outwardly of the rotating member. This force, at the wide base of each tapering nozzle 31, changes to static force which functions to deliver a powerful jet or stream of fluid outwardly and substantially radially of the rotating member. Since these jets are constantly delivered during the rotation, the jets after discharge have a flat-wise lateral movement away from the rotating member, the general direction of which is tangential of the member at the point

of discharge. As a result, when the disk rotates at a proper speed, the lateral movement of each jet causes regions of decreased pressure to form behind each jet.

5 The regions of decreased pressure produced by the cavitating effect of the jets are utilized to cause a flow of fluid to be pumped. In the present instance, this end is accomplished by providing an annular and radially extending 10 passageway 42 (Fig. 1) within the disk 27, which passageway extends from the hub portion approximately to the periphery of the disk. Transverse reinforcing walls 43 provide adequate strength in the unit. The disk has an 15 annular wall 44 disposed concentrically of the shaft 12 to define a port 45 located centrally of the disk and communicating with the passageway 42. The casing section 19 has an axial port 46 therein which is defined within the 20 casing by an annular flange 47 arranged snugly to encircle the outer end of the annular wall 44 on the disk. A tubular nipple 48, having screw-threaded engagement with the casing section 19, communicates with the port 46 and, 25 in turn, is arranged to receive a suitable conduit 49 by which communication with a source (not shown) of fluid to be pumped, such as a container to be evacuated, may be established.

The annular passageway 42 communicates 30 with the region of decreased pressure behind each jet. Thus, a short bore 50 (Figs. 1 and 3) in each projection leads from the passageway 42 to a port 51 located on the annular face of each projection 28 immediately behind the advancing edge of said projection. As the disk rotates, therefore, the accumulative effect of 35 all of the regions of decreased pressure is utilized to produce a flow of fluid to be pumped through the conduit 49, nipple 48, ports 46 and 40 45, passageway 42 and bores 50 to discharge through the ports 51 into the regions of decreased pressure.

While the method of producing regions of 45 decreased pressure by the cavitating effect of a plurality of powerful jets of the fluid is, of itself, operative, it has been found that, by providing means for preserving the character of each jet substantially until the working or cavitation producing force thereof is expended, the efficiency 50 of the pump may be materially increased. The present invention embodies means for accomplishing this purpose in the nature of a plurality of elements arranged successively to interrupt each jet and along which the interrupted jets travel while cavitating. These elements, as shown in Fig. 2, comprise relatively 55 thin, flat blades 52 rigidly secured at spaced intervals throughout the passageway 25 between the compartment 22 and bore 24.

60 The formation and dimension of each blade, as well as the disposition thereof with respect to certain other parts associated therewith, is definite. In considering the blades and the disposition thereof, only a single blade and its relationship to one or two jets need be discussed. Each blade is so disposed within the passageway 25 that one end thereof is closely adjacent to the peripheral face of the projections 28, whereby the blade interrupts each passing jet. 65 The movement of any single particle of fluid as it is discharged from a nozzle is both outwardly and in the direction of rotation of the disk, the theoretical line along which said particle travels being the resultant of the forces 70 producing said outward and lateral movements.

The blade extends generally along the line of this resultant with the rear face 53 of the blade located on the line of said resultant. The inner end of the blade is preferably sharpened substantially to a knife-edge as may be seen at 80 54 to interrupt the jet cleanly.

If it is now presumed that the disk is rotating so that a jet has just been interrupted by a blade, the relationship of parts is indicated at A (Fig. 2). The jet, as the disk continues to 85 rotate, will be discharged toward the rear side of the blade to form, together with the blade and the adjacent portion of the projection, a triangularly-shaped region as shown at B. While, as has been stated, the direction of ejection of the jets is substantially radially, it has 90 been found that the capacity of the pump is increased if the nozzles are formed to direct the jets at a slight angle to the true radius of the disk and rearwardly therefrom with respect to 95 the direction of rotation. It has been ascertained that angles up to ten degrees produce satisfactory results. The triangularly-shaped region thus produced defines the region of decreased pressure produced by the cavitating action of the jet, which region increases in size 100 as the disk rotates. The location of the ports 51, immediately behind each nozzle 31, establishes communication with the triangular region just after it has been formed, which communication exists as long as the volume of said 105 region increases.

The length of each blade will depend upon the density of the fluid within the device as well as upon the speed of rotation of the disk and the 110 force of the jet. Theoretically, the length of the blade is such that the contact between the jet and the blade is maintained as long as possible, which is until the working force of the jet or, in other words, the force which preserves 115 the characteristic of the jet, is nearly expended. As a result, the triangular relationship of the elements will be maintained until the end of the jet which engages the rear surface of the blade passes or breaks over the end of the blade. 120

The position of a nozzle when the jet therefrom breaks over the ends of a blade determines the distance between the sharpened ends 54 of adjacent blades. Thus, each jet, as shown at C (Fig. 2), successively encounters a blade substantially at the moment the jet breaks over 125 the outer end of the preceding blade. This arrangement prevents the back pressure, which, of course, will be exerted in the region of decreased pressure as soon as the jet breaks, from 130 being exerted on the port 51 and its associated passageways and conduits.

As each jet is interrupted by one blade, a succeeding nozzle approaches the interrupting end of a preceding blade so that, immediately after 135 any jet has been cut off and has broken over the end of a blade, a succeeding nozzle passes the blade to create a new triangular region. Obviously, this will cause the advancing face of the newly formed jet to force any pumped fluid 140 which was drawn into the previous triangular region outwardly from between the blades into the bore 24, which may be termed a volute. Inasmuch as the outlet passageway 39 from the volute generally communicates with a conduit 145 which leads to a suitable device wherein natural separation of the fluids may occur, the back pressure existing within the device is atmospheric pressure which is not sufficient to break down or destroy the jets. Furthermore, the flow 150

of fluid within the volute, which naturally occurs in a device of this character, is directed away from the jets by the blades and by the natural flow thereof.

- 5 As the device operates, successive operative steps may be observed. First, a fresh supply of fluid is delivered to a rapidly rotating disk, the action of which causes the fluid to flow outwardly of the disk. As the fluid approaches the 10 periphery, it is entrapped in the pockets where the centrifugal force of the then rotating fluid is converted into static force for discharging a large number of relatively thin and very powerful jets from the disk. These jets move laterally at or above a critical speed to produce 15 regions of decreased pressure by cavitation. Each jet is successively interrupted by means which preserves the characteristics of the jet as long as the jet has a cavitation-producing force, where- 20 upon the jet simultaneously passes beyond its preserving means and is interrupted to allow it to disintegrate and discharge any pumped fluid. As each jet disintegrates, succeeding jets, formed and operating in the same manner, effect a com- 25 plete discharge of pumped fluid into the volute, from which it is conducted out of the device.

It will be apparent from the foregoing that a novel pumping device, as well as a novel method of creating and utilizing a pumping force, 30 has been provided. The device is sturdy in construction and embodies few parts subject to wear. Nor may the device be easily broken or disabled in use, inasmuch as only two relatively movable parts are employed.

35 I claim as my invention:

1. In a pumping device, the combination of a container, a rotating member in said container, means on said member for producing by the centrifugal action of the rotating member jets of 40 fluid directed substantially radially of the member and moving bodily substantially in a straight line direction which is approximately tangential of the member at the point of discharge, means for driving said member at a rotational velocity 45 to produce such tangential body movement of said jet at the critical speed at which cavitation occurs, and means for subjecting the source of fluid to be pumped to the decreased pressure created by cavitation.

- 50 2. In a pumping device, the combination of a container, a member journaled for rotation in said container, means on said member for producing jets of fluid directed generally radially thereof, means adjacent said member for interrupting the jets to form jet sections, said means together with a jet section and an adjacent part of said member being arranged to define a region of decreased pressure produced by the movement of said jet section, and passageways 55 communicating between the region and a source of fluid to be pumped.

- 60 3. In a device of the character described, the combination of a container for fluid, a member rotatably immersed in said fluid, a plurality of jet producing nozzle devices on said member, means for dividing said jets into jet sections, means for establishing communication between a source of fluid to be pumped and the regions immediately behind the jet sections and means

for preserving the character of the jet sections until the working force thereof is substantially expended.

4. A pumping device comprising, in combination, a container for fluid, a member rotatable 80 in the container, means for driving said members, jet-producing devices on said member arranged to direct jets of fluid outwardly therefrom, means adjacent said member and in the path of the jets for dividing the jets into sections and then preserving the character of such sections, said means having such a relationship to said member and to the produced sections that the sections travel laterally along said means without deformation and are directed at 85 an angle thereto whereby each section together with said means and a part of said member define a region the volume of which increases as the section moves, and means for establishing communication between said regions and a 90 source of fluid to be pumped.

5. In a pumping device, the combination of a plurality of blades arranged in spaced series, means for discharging a plurality of jets of fluid against said blades and at such an angle 100 with respect thereto that the jets travel along said blades without deformation of the jets occurring, and means for effecting relative movement between said blades and said jets whereby each blade successively passes each jet, said relative moment being at a velocity above a critical point at which regions of decreased pressure are produced by cavitation.

6. The method of pumping which includes the steps of creating regions of decreased pressure 110 by the cavitating effect of moving jet-like bodies of fluid, preserving the characteristics of said bodies during the cavitating action thereof, utilizing the regions of decreased pressure as a pumping force, and interrupting said bodies to 115 permit disintegration thereof and discharge of the pumped substance.

7. The method of pumping which includes the steps of directing jets of fluid angularly against 120 relatively movable members whereby the jets are divided into sections which have relative flatwise and unimpeded movement along the lengths of said members, effecting such relative movement at a velocity whereby cavitation produces regions of decreased pressure between said 125 sections and members, and connecting said regions with a source of fluid to be pumped.

8. In a pumping device, the combination of a container for fluid, a member journaled for rotation in said fluid, means on said member for 130 producing jets of fluid directed generally radially thereof, means arranged in series adjacent said member and in the path of said jets for dividing said jets into sections, said means being disposed at an angle which substantially conforms 135 to the direction of lateral motion of the sections whereby the inherent nature of the sections is maintained, and is angular with respect to the direction of discharge of the jets, whereby each section and a jet dividing means define a region in which pressure is decreased by cavitation, and passageways leading to each region.

HOWARD W. PARKER.
